BY-PRODUCT COKE OVEN

Paul M. Pinckard, Kalamazoo, Mich.

Application July 3, 1947, Serial No. 758,948

25 Claims. (Cl. 202—134)

1

This invention relates to an improved by-product coke oven in efficiency of heating same and a new conception involving reaction zone controls affecting the basic fundamentals of the art. This work is an improvement in two former patents granted me, U. S. 1,888,012, issued November 15, 1932, but filed June 24, 1930, and U. S. 2,208,053, issued July 16, 1940. Both bear the same title as this invention, though they had but one objective in common stated in their specifications, and that was to lessen chamber losses of gas to the flues. Although one worked on that problem from the chamber providing a reduction in volume and pressure there and the other considered it from the heating flues. Now the latter provided real progress toward a tough engineering problem in the regenerators and the advantages gained are retained herein, but perfected. Likewise the cool zone by-pass is retained but enlarged into temperature and pressure controls of the reaction zone by establishing a system of circulation gas to the oven, being controlled by oven pressures which are modified 25.6% by a full application of top by-pass in any type of oven having a cool roof. So naturally the brand new principles of the measured load in the oven to control yields, quality of gas and rate of formation is dependent on combination with the by-pass to a very important extent. In fact, the means of introducing circulation gas to the oven is arranged in the oven roof as well as by-pass but certainly the objectives are more important and my work backed by a lot more certain knowledge even though the teachings of U. S. 1,888,012 were proven in every respect and 11.5% increase in benzene and increase in the hydro-carbon content of the gas, as well as a drop in temperature in the standpipe of 70 degrees C. Taking absolute zero at minus 273 degrees C., 70 divided by 273 equals at one, two hundred and seventy third for every degree C., 25.6% drop in oven pressure and volume, under the gas laws. Thru this circulation gas which is controlled by oven back pressure itself, controls are established over the reaction zone, through an arranged diffusion of an admixture of gases, provided with a control of the admixture which control in turn is activated by the back pressure in the oven, itself. Some moderate pre-heating of the gases so introduced, prior to entry to the reaction zone, by arrangement of initial vertical and horizontal travel in the oven roof, for gases so introduced. By "reaction zone" I mean the free zone above the leveled coal charge, although the reactions start in the solid mass, where the temperature

2

slowly rises while the temperature of gases in the reaction zone under back pressure remains almost constant, as affected by the basic design provisions in the heating flues as constructed. In Europe where the coking schedules are not, generally speaking, as short as in the United States, the temperatures in the reaction zone, are also above 800 degrees C. the effect in the gases in addition to the normal heat of release in reactions of a constant, stable, and unobstructed heat drive from the heating flue arrangement. Now, April 1, 1941, an improvement in U. S. 1,888,012, U. S. 2,236,782, was granted the present inventor. It provided for the placement of catalysts in the by-pass and the return of the by-pass to the reaction zone, if desired. So henceforth, I will make no particular distinction in the placement of a by-pass arranged in cool portion of oven roof for benefit of gas temperature reduction, as to whether it returns to the reaction zone, in physical arrangement or not. It is a well known fact that when the solid mass reaches 750 deg. C. and passes it and the gases find no further relief thereto in the reaction zone above, only lean gases are produced thereafter. Now it is proposed that while maintained optimum rate of distillation and probable benefits of momentary contact with walls, that the second chance at optimum temperature for rich gas hydrocarbon formation be provided for the gases in the admixture of gases at the point of emergence into the "free" reaction zone, above the leveled coal charge. In the United States especially, where higher temperatures are carried, the benefits of the full by-pass arrangement shown in Figure 7, is recommended by the writer, above the provision for return to reaction zone, because the distance downward to optimum temperature dilution is greater.

Two gas holders are recommended for the circulation gas, one to provide a maintained pressure on the circulation main, and the other, to provide a reserve and a feeder to the holder for the circulation main. They can be filled gradually to avoid disturbance of existing "send out" requirements in present distribution arrangements, and then, "written off" much as is the case in circulating ammonia liquor in the collecting main spray system which provides a "dividend" in further liquor condensed from the gases. The comparison is apt in the circulation gas system for a measured oven load with controls activated by the back pressure in the component ovens in a battery of ovens, for elimination of air dilution in the battery and temperature con-

ditioning of the reaction zone gases by such a controlled dilution of an admixture of gases, and further diffusion provisions arranged in the oven roof. The term "a circulation gas" is used in a generic sense, for any gas or admixture of gases.

In the heating flues arrangement this invention eliminates the crossover flue system, while maintaining equal regenerator efficiency for underfiring without counterflow to gas. Besides the shorter coking schedules:

In the United States, another contributing factor to somewhat higher gas temperatures is inherent in the crossover flue oven design, as crossover flues inevitably cause a hot roof, and necessitate the sacrifice of a black depth of coke to correct it. Now, in this invention the crossover flue is eliminated as the previously solitary means of providing a regenerator for separate pre-heating of low quality gas and air, without counterflow between gas so pre-heated and products of combustion to stack, so that in event of leaks no gas is lost to stack. Now the crossover flue, involved an exchange of heat between two adjacent heating walls. This invention becomes the second to have the important regenerator feature. This invention eliminates the "cross-over" as harmful to gas temperature at the top, and becomes the only oven with a selective exchange in a heating wall and the important regenerator condition of absence of counterflow at the outside regenerator walls lengthwise of the ovens. And in the perfection of this, herein every inch of available oven support has been provided to make this probably the strongest under oven support every offered in a modern oven design.

A 26 inch width of flue by the customary approximate 12 inch lengthwise of the wall is recommended. The key to strengthening an oven wall lies in the flue separation brick whether the alternate interlocking juncture in the wall, is a bottle brick with a modified end at the interlock, or the T brick. The so-called hammer head is a T brick. Now, if the latter is used, a joint should be provided well back of the T.

I recommended the middle road of an unmodified taper juncture in the wall interlock, and fullest backing of the wall in winged shoulders at the flue corners.

Strengthening the horizontal flues by making them smaller is good.

Now, I suggest that a portion of the area provided by the wider flue be used to strengthen the flue separation brick as the key to any other efforts to strengthen the oven wall. Having provided absence of counterflow in the outside regenerator walls, they are adaptable as shown to the well known under jet fuel gas feed—probably the longer jet would be used.

But I also provide efficiency in lateral fuel gas feed in gun fired feed at regenerator face that has separate side service to No. 1 outside flue, which has the advantage of less decomposition of fuel gas and better working conditions for the men. It is obvious that with the special direct feed to the outside flue only, that the velocity can be controlled at point of entry and that the #1 flue nozzle can be eliminated therein, as it would be in the under jet method.

The outside flue bears the brunt of radiation at the jamb well left for expansion at both ends from the oven face brick. With special feed to the outside flue, these losses can be overcome. With No. 1 flue warm, No. 2 is warm, and No. 3,

onward always heated well, and with the special lateral gas feed to the outside flues.

A very moderate column would be sufficient for mounting the oven mat, for the advantages of air cooling, with the special lateral gas feed to the outside flues and with the lateral gas feed ducts feeding the other flues in adjacent heating walls placed intermediately of two heating walls, above the outside regenerator walls, where there is never any counterflow. These are walls 102 Fig. 1, where placement for adaption for under jet is shown. These could feed gas to alternate concurrent, non-parallel groups of flues in two adjacent heating walls. The exchange of heat being selective in the heating walls, the flue groupings for exchange may vary in number along the walls.

Having a selective exchange it is proposed that the flue groupings at the center may be built for one and one exchange while the outside flues may be built for the two and two exchange. This proposal is to moderate the friction load on the stack at the point where it is greatest, the center of the oven, to insure a minimum of gas travel from the chambers to the flues inherent in a low stack differential. Figure 1 is a twice broken vertical, cross sectional view. A section of the roof 30 and another section of same—2, showing a section of a by-pass 24 and flue inspection port 17 with cover 18, top and bottom sections of a coking chamber 19, with top level of coal charge 22 and reaction zone above 23. A broken view of a vertical branch leading from reaction zone 23 to by-pass 24. Top and bottom of vertical flue 13, horizontal flues 16 with the communication 15 through the cap brick to vertical flues 13. Note that the top levels of the horizontal flues are at least six inches below the top level of the coal charge 22 to protect the gases in the reaction zone 23 from over heating. Gas nozzles 20, at vertical flue floor level, permits scrubbing by return waste gases to air port in vertical flue floor, formed by junction there of channels 11 and 12 connecting with the regenerator. Fuel gas ducts 25 and phantom view 12 of mean placement of special lateral feeds to outside flues only, at regenerator portion face. Top of outside regenerator portions 9 and top of inside regenerator portions 10, outwardly tapered support 8, chequer shapes 7, bus flues 5, outside regenerator walls 102 and central longitudinal division walls 101, bus flue partition 6, furnishing unbroken outwardly support to meet taper 4, from both wall 102 and wall 101. A mere modification in taper 4 forms three sides of opening 27 from bus flues 5, which can be clearly seen in a glance at the second open regenerator section from the left where the formation of 27 opening stands out.

The third regenerator from the left is broken to show vertical openings, 28 in chequer shapes 1 and the low center of gravity joints in 7 chequer shapes, "low" centrally of contact at spaced openings with flows of gaseous fluids which scrub joints there. Dotted phantom vertical passages are shown in walls 102, as shown by broken view connected to vertical flue in center of Figure 1, shows placement in outside regenerator walls to ducts to adapt this oven to the well known under jet principle for gas feeds to individual flues from a "basement" below ovens mounted on moderate columns. The same condition of absence of counterflow which led to the selection of walls 102 is uniform lengthwise of the oven in this design so that in event of leaks in adaptions of the under jet, no gas would be

lost to stack. Due to the turn the long jet or "high" jet is indicated.

To return to the provisions for the lateral fuel gas feed. Gas nozzles 20 are at floor level of vertical flues 13, hence are scrubbed by waste gases on the return to the air port which at the temp. of the flue inhibits carbon. But that reaction is only quite effective at elevated temperatures. Hence this oven will rely on the old reliable air decarbonization. As well described in my remote basic to my U. S. 2,208,053, July 16, 1940, U. S. 2,049,136, issued July 28, 1936, the general nature of the windbox fuel gas and decarbonizing controls are well known to those skilled in the art, for admission or exclusion of air, or blast furnace or producer gas or return in waste gas to leads to stack, same being activated by movement of a cable according to individual tie up of pulleys or drums moved by cable or arm attachment to cable movement for slack or pull up. Said cables running lengthwise of battery. I intend use of gravity left, plunger type covers for dampering lead to stack arch and also low quality gas compartment. The reversing decarbonizing control machinery is well known. A butterfly valve set uniformly by a quadrant. Concave corrugated outer surfaces to wind boxes designed to bind a poured refractory around wind box to seal joints thereof.

Figure 2 is a broken longitudinal view, showing a portion of the roof 2 in its relationship to the horizontal flues 16 and their selective tie up with the vertical flues through openings 15 in the vertical flue cap brick. The grouping for exchange between the vertical flues being entirely selective results in the showing of horizontal flues 16 in varied length along the heating wall. The arrows indicate only one of several possible arrangement of flows. Note that in this figure the one and one exchange is shown at the center of the oven and the two and two exchange at the outside. This would lighten the friction at the center which is the greatest distance from bus flue inlet and outlet and would lessen gas travel losses from coking chamber to flues.

Figure 3 shows the regenerator shape 7 with openings 28 and low center of gravity joint provisions.

Figure 4 shows an enlarged section of the bus flues 5, bus flue partition 6 with support features.

Figure 5 is a longitudinal broken view of the top structure 2 and 30, coal lorry tracks 44, by pass 24 with sections there of 32 and 46, vertical branches there of 31, 45 and standpipe 47, lid 48, collecting main 49, riser 50 crossover main showing butter fly valve 51, controller 54, motor 53 linkage to butter fly valve 52. This is the crossover main control of gases leaving the battery at the cross-over main. Returning to the oven in Figure 5, the dotted line represents top of leveled coal charge. The provisions at the left of the roof for a shelf or catwalk for the placement of circulation gas controls. Circulation gas main 51, pipe connection 55, with valve 56, linkage to motor 53, vertical passage or well 37 having connection at the bottom portion with 37 leading vertically up to horizontal channel 34 to vertical branch 33 (which may also serve as a charging hole to the chamber of the oven). Returning to horizontal channel 34, back pressure lead line 35 opening at 38 facing direction of standpipe (about a 2½" line with 1" line leading off it to the meter while it continues on to the back pressure controls, controlling and activating motor on circulation line). 35 connecting 75

controller 40, 41, 42, 58 and motor 53 with linkage to valve 56 on circulation line 55.

Figure 6 more clearly and fully shows a type of control apparatus that has given satisfactory, economical service for thirty years. Its simplicity and low cost recommend it until the equipment manufacturers adapt to this new outlet for their wares. The lines carrying the back pressure to the meter in the 1" offtake from the 2½" line have been explained. The 1" line connects by base connection to meter having a pipe continuation inside, that extends upward through an aqueous fluid pipe 67 into a bottomless float 69 opening into it above the level of the fluid. Gas pressure causes the float to rise or fall, the pen attached to the float making a recording on a chart fastened around a cylindrical clock type drum. The 2½" line 39 continues up through a fluid (usually water) in a 14 inch x 10 inch deep vessel 41, opening above fluid into a bottomless float 42 resting in the fluid and having linkage 58 with a balance on one side of a fulcrum, 62 contacts 63 and 64 at one end of the balance and a regular scale balance at the other having weight 61, fastened at 59, adjustment nut 60, contacts 64 and 63 as the back pressure varies operate one of two breakers in circuit with motor 53 control of valve 56 in circulation line 55.

Figure 7 shows the type of installation, that I recommend for the United States, where the full effects of this invention must be brought into play to dilute the reaction zone temperatures down to 750 degrees C. The short coking schedules here make this so. There is nothing new about raising the lorry tracks but some reinforcement is desirable in Figure 7 installation. Only one of the lorry tracks will need to be reinforced, however, as a glance at Figure 7 will show. The other track has the whole roof under it. So reinforcing but one side of the raised tracks is not too much of a job.

I am convinced that any dilution of gas short of that required to produce 750 degrees C., is not enough. In other words, I look on 750 deg. C. as the critical point. Stability and constancy of maintained heat in the reaction zone is a characteristic of any oven, with level of stability, basic in the heating provisions.

The big drive is to arrange for maximum admixture and diffusion to attain the goal set in diluting and conditioning the admixture of gas receiving the gas rising from the solid charge.

I trust that I've made it clear. The benefits do not stop with pyrolysis factor benefits. The air dilution in present batteries of ovens is considerable at all times in some of the ovens.

There is known evidence that 750 deg. C. is the critical point in rich gas formation.

The late Professor Parr of the University of Illinois, who did some distinguished work on calorimetry and gas analysis from the lowest temperature, carried on some experiments at Urbana, Illinois, on Illinois coal. He reported that gently pre-heated coal treated in ovens at nearly normal temperatures for five hours ceased to produce rich gas at 750 degrees C. in the mass.

In providing these controls over basic oven factors to increased yields and richer gas, oven pressures are controlling factors. These are based on provided constant readily available knowledge on the part of the operator, of what conditions really prevail in the component ovens of a battery, and a coke oven designed for strength and efficiency and maximum flexibility,

that should be pleasing to the steel, gas utility, and chemical field. I sincerely gave their needs long consideration.

Having thus described my invention in but a few constructions under which it may be built, I claim the full scope of the appended claims.

I claim:

1. In a coke oven having a coking chamber and heating flues on each side of the coking chamber, regenerators below the coking chambers, each regenerator composed of two independent main longitudinal sections communicating with at least two heating flues on the same side of the coking chamber, which are grouped together for exchange of heat, each regenerator section having at least two independent rows of spaced, vertical ducts, supporting walls separating the adjacent regenerator sections, each section being formed of a series of superimposed horizontal bricks extending between said supporting walls, each brick having two vertical openings forming said ducts, each brick having a depressed groove in the upper surface between said openings and a corresponding projection downward from the lower surface, means for supporting the lowermost row of bricks between said openings and a wall supported between the openings by the uppermost row of bricks, said supporting walls and last named wall which support said coking chamber and heating flues, forming an integrated structure.

2. In a coke oven having a coking chamber and heating flues on each side of the coking chamber, regenerators below the coking chambers, each regenerator composed of two independent main longitudinal sections communicating with at least two heating flues on the same side of the coking chamber, which are grouped together for exchange of heat each regenerator section having at least two independent rows of spaced, vertical ducts, supporting walls separating the adjacent regenerator sections, each section being formed of a series of superimposed horizontal bricks extending between said supporting walls, each brick having two vertical openings forming said ducts, each brick having a depressed groove in the upper surface between said openings and a corresponding projection downward from the lower surface, means for supporting the lowermost rows of bricks between said openings and a wall supported between the openings by the uppermost row of bricks, said supporting walls and last named wall which support said coking chamber and heating flues, forming an integrated structure, in which the lower portions of the longitudinal supporting walls and the wall below the bricks, form regenerator bus-flues, the supporting walls having projecting tongues beneath and further supporting the lowermost row of bricks, said tongues having spaced vertical groove therein forming the entrance to the vertical ducts in the regenerator sections.

3. In a coke oven having a coking chamber and heating flues on each side of the coking chamber, regenerators below the coking chambers, each regenerator composed of two independent main longitudinal sections communicating with at least two heating flues on the same side of the coking chamber, which are grouped together for exchange of heat, each regenerator section having at least two independent rows of spaced, vertical ducts, supporting walls separating the adjacent regenerator sections, each section being formed of a series of superimposed

horizontal bricks extending between said supporting walls, each brick having two vertical openings forming said ducts, each brick having a depressed groove in the upper surface between said openings and a corresponding projection downward from the lower surface, means for supporting the lowermost row of bricks between said openings and a wall supported between the openings by the uppermost row of bricks, said supporting walls and last named wall which supported said coking chamber and heating flues, forming an integrated structure, in which the lower portions of the longitudinal supporting walls and the walls below the bricks, form regenerator bus-flues, the supporting walls having projecting tongues beneath and further supporting the lowermost row of bricks, said tongues having spaced vertical groove therein forming the entrance to the vertical ducts in the regenerator sections, in which the lower portions of the longitudinal supporting walls and the lower wall below the bricks form two regenerator bus-flues, said bus flues serving to supply air in two of bus-flues and waste gas return in others or reverse or low quality gas may be introduced in outer bus-flues without counter flow to returning waste gases, said bus flues extending the length of regenerator.

4. In a coke oven having a coking chamber and heating flues on each side of the coking chamber, regenerators below the coking chambers, each regenerator composed of two independent main longitudinal sections communicating with at least two heating flues on the same side of the coking chamber, which are grouped together for exchange of heat each regenerator section having at least two independent rows of spaced, vertical ducts, supporting walls separating the adjacent regenerator sections, each section being formed of a series of superimposed horizontal bricks extending between said supporting walls, each brick having two vertical openings forming said ducts, each brick having a depressed groove in the upper surface between said openings and a corresponding projection downward from the lower surface, means for supporting the lowermost rows of bricks between said openings and a wall supported between the openings by the uppermost row of bricks, said supporting walls and last named wall which support said coking chamber and heating flues, forming an integrated structure, in which the lower portions of the longitudinal supporting walls and the wall below the bricks, form regenerator bus-flues, the supporting walls having projecting tongues beneath and further supporting the lowermost row of bricks, said tongues having spaced vertical groove therein forming the entrance to the vertical ducts in the regenerator sections, the outside supporting walls providing placement for rich gas ducts if adapted to well-known under jet rich gas feed ducts to individual flues, as there is never any counter-flow with waste gases at outer supporting walls.

5. In a coke oven having a coking chamber and heating flues on each side of the coking chamber, regenerators below the coking chambers, each regenerator composed of two independent main longitudinal sections communicating with at least two heating flues on the same side of the coking chamber, which are grouped together for exchange of heat each regenerator section having at least two independent rows of spaced, vertical ducts, supporting walls separating the adjacent regenerator sections, each section being formed

of a series of superimposed horizontal bricks extending between said supporting walls, each brick having two vertical openings forming said ducts, each brick having a depressed groove in the upper surface between said openings and a corresponding projection downward from the lower surface, means for supporting the lowermost rows of bricks between said openings and a wall supported between the openings by the uppermost row of bricks, said supporting walls and last named wall which support said coking chamber and heating flues, forming an integrated structure, in which the lower portions of the longitudinal supporting walls and the wall below the bricks, form regenerator bus-flues, the supporting walls having projecting tongues beneath and further supporting the lowermost row of bricks, said tongues having spaced vertical grooves therein forming the entrance to the vertical ducts in the regenerator sections, fuel gas ducts which are central of two adjacent heating walls, said ducts simultaneously servicing alternate non-parallel groups of flues in said walls, independent fuel gas feeds provided at regenerator faces for the outside flue which is the first flue thereto, to overcome radiation losses.

6. In combination with a by-product coke oven a coking chamber formed between two heating walls having a cool portion of oven roof at the top of the oven, means for admitting circulation gases to top of oven chamber, controls for said means, said controls being activated by the pressure of the oven gases, a by-pass in said cool portion of oven roof with vertical branches therein, connecting to the coking chamber, a heating wall with vertical flues therein, conduits connecting the flues to form groups, said groups of flues increasing in number outwardly from at least two flues at the center of the coke oven, to moderate gas pressures in the flues and minimize friction load and reduce gas travel losses, a plurality of regenerators separated by central longitudinal walls, each group of flues communicating with alternate sides of a central longitudinal regenerator wall, each regenerator having therethrough two rows of vertical, spaced ducts independent of each other, low center of gravity joints between the rows of ducts said joints extending lengthwise of each regenerator, bus flues connected to said ducts, the regenerator brick structure forming intermediate support between said longitudinal walls for the above coke oven structure, said sections being provided with absence of counterflow at the outside retaining walls of the oven, lengthwise of regenerator.

7. A coke oven comprising a coking chamber, a roof above the coking chamber, a by-pass in said roof having vertical openings communicating with said coking chamber, a gas exhaust conduit at one end of said oven chamber, said exhaust conduit in gas flow connection with the by-pass; gas inlet means at the other end of the coking chamber for the introduction of circulation gases; control means for regulating the flow of gas through said inlet means; said control means actuated and regulated by the gas pressure in the coke oven chamber to introduce, circulating gas to maintain a fixed pressure in said chamber, said gas inlet means being in gas flow connection with said oven chamber and said by-pass.

8. A coke oven comprising a coking chamber, a roof above the coking chamber, a by-pass in said roof having vertical openings communicating with said coking chamber and some serving as charging openings, a gas exhaust conduit in gas flow

connection with the by-pass; gas inlet means at the other end of coking chamber for the introduction of circulation gases; control means for regulating the flow of gas through said inlet means; said control means actuated and regulated by the gas pressure in the coke oven chamber to introduce, circulating gas to maintain a fixed pressure in said chamber, said gas inlet means being in gas flow connection with said oven chamber and said by-pass.

9. In combination, defining a means, with a by-product coke oven, a coking chamber formed between two vertical heating walls having flues therein, said chamber having a cool upper roof portion, a controlled means of admitting a circulation gas to the chamber reaction zone, said controls activated by gas pressure in the chamber, said means moderating relatively stable reaction zone gas temperatures as affected by unobstructed heating drive, a by-pass for gases in said means lessening gas pressure in the cool portion of roof, said by-pass having vertical branches to chamber, certain of said vertical branches provide coal charging holes thereto, said vertical branches being of approximately the diameter of the chamber athwart the width thereof, said by-pass provided with catalysts placed therein, further arrangements for circulation gas, in horizontal and vertical roof channels, said means provided in said channels, to pre-heat circulation gases, prior to introduction of said circulation gas to the reaction zone.

10. In a by-product coke oven defining a means in combination, a regenerator having two outer walls and a central wall lengthwise thereof, heating wall with flues therein, communicating alternately in even adjacent groups of flues, each half of a said group of flues communicating with an alternate side of central longitudinal regenerator division walls, spaced vertical ducts lengthwise thereof, in outside and inside sub-sections, said sub-sections being centrally independent, low center of gravity joints therein, means providing for absence of counterflow at outside regenerator walls, means for placement of fuel gas feeds vertically to independent flues providing means for adaption of this oven to the well known under jet fuel gas feed, without counterflow of fuel gas to waste gases in the vertical fuel gas feeds leading to each vertical flue in a heating wall, in placement of said fuel gas feeds in said outside regenerator walls, flows being in uniform direction at said walls, never counter-flowing waste gases leading to a stack so that no fuel gas, so introduced can be lost to stack.

11. In a by-product coke oven, defining a means in combination, a regenerator having two outer walls and a central wall lengthwise thereof, a heating wall with conduits connecting vertical flues therein in communication in alternate equal numbers of flues which communicate with an alternate side of central longitudinal regenerator division wall, spaced vertical ducts lengthwise of regenerator each side of said central wall, in independent rows lengthwise of regenerator, means provided for low center of gravity joints therein, centrally of said rows, said means being placed lengthwise of regenerator, said rows of ducts being over two independent bus flues on each side of said central longitudinal regenerator wall, bus flue partition inter-locked with side walls furnishing support to said rows of sections, said side walls formed by said central and outer regenerator walls, means providing absence of counter flow at the outer walls lengthwise thereof, at the outer

walls which define a regenerator, said outer walls providing means for placement for vertical fuel gas feeds leading to individual flues without counterflow to waste gas or loss of gas to stack, in adapting to the well known under jet fuel gas feed, and means for low quality gas preheating in outer sub-sections of regenerator.

12. With a by-product coke oven formed between two vertical heating walls, said oven having a cool roof, in combination, a coking chamber having a cool roof there to arrangements therein for introduction of circulation gas to the chamber thereof, said arrangements being vertical and horizontal channels in said roof to provide a gentle pre-heating of said circulation gas, prior to entry into said chamber, further arrangements for by-pass for gases in the cool portion of oven roof, said by pass having vertical branches to said chamber, said circulation gases being provided with controls, said controls being activated by gas pressure conditions in the chamber, providing a measured admixture of gases in the reaction zone, within limits provided by cool by-pass, in a balanced relationship thereto.

13. With a by-product coke oven formed between two vertical heating walls, said oven having a cool roof, in combination, a by-pass arranged in cool portion of oven roof, having vertical branches to oven chamber, said means providing initial reduction in gas volume and pressure in standpipe which conveys gases from oven, in combination with further provisions of horizontal and vertical channels for introducing circulation gas into the oven chamber, to control temperature of gases therein by admixture therewith, to provide more nearly optimum temperature to gases in the admixture, at reception of gases emerging from the solid charge, said circulation gases being provided with controls activated by a measured gas pressure in the chamber.

14. With a by-product coke oven formed between two vertical heating walls, said oven having a cool upper area of the roof thereto, in combination, a by-pass arranged in cool portion of oven roof, having vertical branches to oven chamber, and a means of introducing circulation gas to the oven chamber, to provide dilution of temperature condition of gas therein by admixture therewith, within limits of reduction in volume and pressure due to cool by-pass, said circulation gas being provided with controls, said controls being activated by measured gas pressure in the chamber, certain of vertical branches in said arrangements, provide coal charging passages for the oven.

15. In combination with a by-product coke oven, a regenerator having two outer walls and a central wall lengthwise thereof, a coking chamber formed between two vertical heating walls, a cool portion of oven roof at the top of the oven, a controlled means of admitting circulation gases to the coking chamber, said control activated by gas pressure in the chamber a by-pass arranged in cool portion of oven roof with vertical branches to chamber, reduces gas pressure, moderating gas pressure losses to flues, a heating wall with vertical flues therein, conduits connecting the flues in selective relationship for chosen exchange, having heat exchange in smaller groups of flues centrally of oven, to moderate flue pressures there and minimize friction load and reduce gas travel losses from the chamber, a plurality of sections of regenerator having a central longitudinal wall, said flues in each heating wall communicating with an alternate side of central longitudinal regenerator wall, said sections arranged in two rows

of spaced vertical ducts, said rows of ducts being centrally independent of each other, low center of gravity joints between said rows of ducts, extending lengthwise of regenerator, bus flues thereto with partition thereof, said partition forming intermediate support with side walls for said sections above, means provided in said sections for absence of counterflow at outside retaining walls lengthwise of regenerator.

16. With a by-product coke oven having a cool roof, a coking chamber formed between two vertical heating walls, in combination, a regenerator having two outer walls and a central wall lengthwise thereof, a by-pass arranged in cool portion of oven roof having vertical branches to coking chamber thereof, said by-pass reducing gas pressure, providing reduction of gas travel losses to stack, and an initial drop in volume and pressure, a controlled means of admitting circulation gas to the oven for gas temperature dilution by admixture and diffusion, said circulation gas control valve mechanism being activated by measured gas pressure in the oven chamber, said heating walls with flues therein grouped in smaller groups of flues at oven center to lessen chamber gas loss there, and for exchange of heat which is selective in selected even groups of flues along a heating wall, said flues communicating with an alternate side of central regenerator division wall with two sub-sections of the regenerator, said sub-sections formed by two rows of spaced vertical ducts lengthwise of regenerator, said rows of vertical ducts being integrated, but centrally independent, low center of gravity joints between said rows of ducts lengthwise of regenerator, but flues beneath, inter-locking support being formed therein between bus flue partition and walls thereto, bus flue openings therefrom leading to spaced vertical ducts, said bus flue openings to sub regenerator sections above, said openings being formed on three sides by modification of taper from walls and on the one remaining side by centrally tapered support thereto.

17. In combination with a by-product coke oven having a cool roof, a coking chamber formed between two vertical heating walls, defining a means, in combination, a controlled means of admitting a circulation gas to the chamber, forming an admixture of gases therein providing a dilution of temperature of gases in reaction zone, to control a revision of temperature in gases for improvement in pyrolysis factors of carbon compounds, rate of formation of said compounds at early stages of gas formation, and to provide elimination of air dilution of gas in oven chamber on a battery of ovens, a by-pass for said gases arranged in cool portions of chamber roof having vertical branches thereto, certain of vertical branches incidental to said combined arrangements providing coal charging passages to the chamber, said combination and said means, providing less free carbon in the gas and a control for improvement of gas quality, products rate of formation, and a measured pressure load, in component ovens in a battery of ovens.

18. In combination with a by-product coke oven having a cool upper roof area, a coking chamber formed between two vertical heating walls, a controlled means of admitting circulation gas to chamber for a measured gas load therein, said controlled means having controls, said controls activated by gas pressure in the chamber within limits of important reduction of volume and pressure, said reduction of volume and pressure due to a by-pass of oven chamber arranged

in cool portion of chamber roof with vertical branches thereto, horizontal and vertical channels in roof thereof provide gentle preheating of said circulation gas, prior to entry to said chamber, certain of vertical branches to chamber providing coal charging holes thereto.

19. In combination with a by-product coke oven, said oven having a cool portion in upper roof area, a coking chamber, said chamber formed between two heating vertical walls, a controlled means of admitting circulation gas to the chamber, said controls activated by gas pressure in the chamber, important reduction of pressure and volume due a by-pass of chamber with vertical branches thereto, said by-pass arranged in cool portion of oven roof, said by-pass limiting loss to flues by modifying pressure, a heating wall with vertical flues therein, a heat exchange confined thereto, having adjacent groups of flues, conduits connecting even number of flues in groups, for exchange of heat, a small number of vertical flues in group at the center of oven, to minimize chamber gas losses in a heat exchange between adjacent flues, said adjacent flues communicating with an alternate side of central regenerator wall, each main regenerator division having two rows of vertically spaced ducts lengthwise of oven, bus flues forming interlocking intermediate support thereto, said rows of vertical ducts being centrally independent, low center of gravity integrated joints therebetween, means providing for absence of counterflow at outer regenerator walls lengthwise of the oven, where gas may be preheated when under firing, with inner sets of ducts heating air next to sets carrying waste to stack.

20. In combination with a by-product coke oven having a cool roof area, a coking chamber formed between two vertical heating walls, a controlled means of admitting circulation gas to chamber, a by-pass arranged in cool portion of oven roof, said controls activated by gas pressure in said chamber, important reduction in pressure and volume due to said by-pass of chamber, vertical branches from said by-pass leading to chamber, certain of the vertical branches incidental to said combined arrangements providing coal charging passages to the oven, said arrangements providing a controlled gas load in the oven, elimination of air dilution in the chamber, and improved pyrolysis factors in the reaction zone of the coking chamber.

21. With a by-product coke oven formed between two vertical heating walls, said oven having cool roof area, defining a means, in combination, a regenerator having two outer and one central wall, a heating wall with flues therein, said flues in communication in alternate equal numbers with one side alternately of a central longitudinal regenerator wall, for an exchange of heat, said regenerator having two outside walls longitudinal thereof, spaced vertical ducts lengthwise of regenerator in centrally independent rows, low center of gravity joints therebetween lengthwise of regenerator, sub-sections of regenerator thus formed above two independent bus flues, communicating therewith, like sub-sections of regenerator on each side of said central wall, said bus flues furnishing support, interlocked from tapered partition centrally to taper from walls, means provided for absence of counterflow in outside walls lengthwise of regenerator, said means providing an area in and around and above outside walls, lengthwise of regenerator, for sound placement of heating gas feeds with-

cut loss of gas to stack in an exchange of heat of flues in the same heating wall.

22. With a by-product coke oven, having a coking chamber formed between two vertical heating walls, each wall having flues connected by conduits in groups of at least two flues for exchange of heat, each heating wall provided with a regenerator, said regenerator having two outer walls and a central wall, extending beneath each heating wall longitudinally thereof, means providing like vertical flows of gaseous fluids, each side of said central wall in integrated centrally independent pairs of sections, integrated centrally thereof, half of said flues in each heating wall communicating with one pair of sections and remaining half of flues communicating with the other pair of sections of regenerator, said sections having low center of gravity joints, centrally of said spaced vertical ducts, like flows lengthwise of regenerator in said subsections thereof, providing means of preheating low quality gas without counter flow in the outer portions thereof, and means for a selective arrangement of flues in adjacent groups of flues, said groups of flues each connected by conduits for exchange of heat between any selected even number of adjacent flues in the same wall.

23. With a by-product coke oven, in a battery of coke ovens, a coking chamber formed between two vertical heating walls, each wall having flues connected by conduits for exchange of heat in groups of at least two flues, each heating wall provided with a regenerator, said regenerator having two outer walls and a central wall extending beneath each heating wall lengthwise thereof, means providing like vertical flows of gaseous fluids, lengthwise of regenerator on each side of said central division wall, in integrated centrally independent pairs of sections, half of said flues communicating with one pair of said sections and remaining half of flues communicating with other pair of sections, said sections having low center of gravity joints, centrally of spaced vertical channels, like flows lengthwise of regenerator on each side of central wall in sub-sections thereof, without counterflow with waste gases to stack, and means for a selective arrangement of flues in adjacent groups of flues, said groups of flues each connected by conduits, for exchange of heat between any selected even group of adjacent flues in the same wall, a fuel gas duct centrally of two adjacent heating walls except at end walls in said battery of coke ovens, said fuel gas duct simultaneously servicing alternate non-parallel groups of flues in said walls, a like fuel gas duct servicing alternate flues at said end walls, independent fuel gas feeds provided at regenerator faces, for the outside flues which is the first flue from said regenerator face thereto, said independent feeds to outside flues tend to overcome radiation losses.

24. With a by-product coke oven defining a means in combination, a regenerator extending beneath a heating wall with groups of vertical flues, in said heating wall, said flues connected by conduits, said flues selectively grouped to provide heat exchange in each group with two main longitudinal sections of regenerator, each half of said flues communicating with one main section of said regenerator, said groups of flues provided with an exchange of heat, with said regenerator below, alternate flues in each group of flues communicating with one side of a central longitudinal regenerator wall in two subsections of regenerator extending beneath each heating wall, a means providing like flows of gaseous fluids lengthwise of

regenerator in spaced vertical ducts, centrally independent sub-sections of regenerator, said sub-sections integrated in low center gravity joints, said sections having bus flues beneath, with partition lengthwise thereof, said partition interlocked with walls, and providing intermediate support.

25. With a by-product coke oven, defining a means in combination, a regenerator having two outer walls and a central wall lengthwise thereof, said regenerator extending beneath a heating wall with conduits connecting groups of vertical flues in said heating wall, said vertical flues selectively grouped to provide an exchange of heat for even numbers of vertical flues, in said exchange the alternate flues in each group of flues each communicate with one side of said central regenerator division wall longitudinally of the oven, said regenerator walls defining two major sections of regenerator, each major section of regenerator being provided with means for like direction of flows of gaseous fluids lengthwise of each section, centrally independent outer and inner sub-sections thereof, low center of gravity joints therebetween, said means providing for absence of counterflow in the outer-subsections of the regenerator, so that the low quality gas may
